US00D535180S

(12) **United States Design Patent** (10) **Patent No.:** **US D535,180 S**
(45) **Date of Patent:** **** Jan. 16, 2007**

(54) **INSERT STUD FOR MOLDED PLASTIC
COMPONENTS**

(75) Inventors: **Patricia Tibbenham**, West Bloomfield, MI (US); **David Dean**, Commerce Township, MI (US); **Wieslaw Zaydel**, Rochester, MI (US); **Michelle Winowski-Zaydel**, Oxford, MI (US)

(73) Assignee: **Ford Global Technologies, LLC**, Dearborn, MI (US)

(**) Term: **14 Years**

(21) Appl. No.: **29/215,913**

(22) Filed: **Oct. 27, 2004**

(51) **LOC (8) Cl.** **08-08**

(52) **U.S. Cl.** **D8/382**

(58) **Field of Classification Search** D8/349, D8/382, 385-388, 391; 411/439-441, 446, 411/448-449, 480, 481, 491

See application file for complete search history.

(57) **CLAIM**

The ornamental design for a insert stud for molded plastic components, as shown and described.

DESCRIPTION

FIG. 1 is a top plan view of an insert fastener showing my new design;

FIG. 2 is a cross-sectional view of the fastener taken along lines 2—2 of FIG. 1;

FIG. 3 is a bottom plan view of the insert fastener;

FIG. 4 is an elevational view of the insert stud;

FIG. 5 is a top perspective view of the insert fastener; and, FIG. 6 is a bottom perspective view of the insert fastener.
